ELECTRONIC GAME CABINET

Harry F. Tiedemann, Reno, Nev., assignor to Nevada Electronics, Reno, Nev., a corporation of Nevada

Filed Oct. 10, 1966, Ser. No. 4,207

Term of patent 14 years

(Cl. D34—5)

Fig. 1

I claim:

The ornamental design for an electronic game cabinet, substantially as shown and described.
